UNITED STATES PATENT OFFICE.

ANDREW WICKEY, OF EAST CHICAGO, INDIANA.

BUILDING CONSTRUCTION.

1,275,345.

Specification of Letters Patent. Patented Aug. 13, 1918.

Application filed January 25, 1917. Serial No. 144,331.

To all whom it may concern:

Be it known that I, ANDREW WICKEY, a citizen of the United States, and a resident of East Chicago, county of Lake, and State of Indiana; have invented certain new and useful Improvements in Building Constructions, of which the following is declared to be a full, clear, and exact description.

This invention relates to building construction, and its principal object is to provide a simple, cheap, light, substantial and efficient structure, designed principally for use in dwellings and apartment buildings. Another object is to provide a combined reinforced concrete and tile floor construction which may be used in dwellings and apartments without the employment of steel skeleton frame work. Another object is to provide a building construction which shall be substantially fire-proof and sound-proof. With these and other objects and advantages in view, this invention consists in the several novel features hereinafter set forth and claimed.

The invention is clearly illustrated in the drawings accompanying this specification, in which:

Figure 1, is a perspective view of a fragment of a building construction, embodying a simple form of the present invention, part of the flooring boards having been removed to illustrate the parts beneath the same; Fig. 2, is a perspective view of a fragment of the structure with certain parts removed to more clearly illustrate other parts of the construction; Fig. 3, is a vertical, longitudinal section taken on the line 3—3 of Fig. 1; and Fig. 4, is a vertical cross section taken on the line 4—4 of Fig. 3.

Referring to said drawings, 5, designates one of the walls or partitions of a building which may be composed of stone, brick or tiles, and it is here shown as one of the partitions of the building, composed in the main, of superimposed tiles. Extending from wall to wall of the building, and through the partitions, are the concrete girders 6, which in accordance with the common practice are reinforced by lengthwise extending reinforcing rods 7, embedded in the girders near their lower sides. At the places where the girders join the partitions, it is preferable to employ additional reinforcing rods 8, near the upper faces 55 of the concrete girders, the reinforcing rods

extending a short distance from the partitions. In cases where there are long spans, it is preferable to employ concrete columns 9, which join the girders as shown in Figs. 1 and 2, and these columns are provided in spaces which are left between the tiles at the places where the columns are to be formed. Usually hollow tiles are provided, and part of the concrete enters the hollows of the tiles, thereby bonding the columns 60 and tiles. It is also preferable to lay a course of concrete, 10, upon the tiles at the floor line, thereby providing an integral reinforced concrete connection between the girders and columns. 70

Between the girders 6, are rows of thin ceiling tiles 11, which extend crosswise between the girders, and said tiles are laid flush with the lower sides of the girders to provide a smooth ceiling which may be completed with a light coat of plaster, and decorated in any desired manner. Said tiles 11, may be hollow, as for instance, they may be provided with lengthwise extending openings 12, and in erecting the 80 floor, part of the concrete of the girders enters said hollows, thereby bonding the girders and tiles together.

Between each pair of girders is a frame work, which forms a brace or bridge for 85 the floor. Said frame work is preferably constructed as follows: Running lengthwise of the girders and contiguous therewith, are boards 13, which extend from the upper faces of the tiles 11, to the upper faces of 90 the girders 6, and between said boards 13, are other boards 14, which run parallel therewith, and also extend from the upper faces of the tiles 11, to the plane of the upper faces of the girders. The boards 13, 95 extend between the partitions, and also between the partitions and outside walls, and at the partitions and walls said boards are connected by crosswise extending boards 15, placed contiguous with the walls or partitions, and other crosswise extending boards 16, are placed between the boards 13, 14, and between the boards 14, 14, as shown, all of the boards being nailed together and forming a bridge work across 105 the floor space. Between each pair of boards, 14, 14, is placed a board 17, which lies flat upon the tiles 11, and is nailed to the boards 14. Said board 17, extends through the crosswise extending boards 15, 110

and is nailed to a block 18, which is spiked or otherwise secured to the partition. Each block is arranged to receive the ends of the two meeting boards. The boards 13, 14, 15 5 and 16, in addition to providing a bridge work for the floor, may comprise the nail strips to which are nailed the flooring boards 19. It will be observed that practically all of the load on the flooring boards 10 is carried directly by the reinforced concrete girders, and that very little of the load is carried by the board frame work; consequently the ceiling tiles 11, may be very thin, inasmuch as they have no heavy load 15 to carry.

In constructing a building in accordance with the present invention, the walls and partitions are erected in the usual manner up to the floor line, and then boards or planks 20, are placed along the lines where the girders are to be formed; said boards or planks 20, being supported by the usual stagg- 25 ing 21, in accordance with the well known practice. The tiles 11, are then laid upon the boards or planks 20, spaces being left therebetween to provide for the reinforced concrete girders. The frame work, comprising the boards 13, 14, 15, 16 and 17, and blocks 18, having been nailed together, and it 30 will be observed that the adjacent boards 13 and ends of the tiles 11, provide the sides of troughs for the reception of the concrete for the girders. The reinforcing rods 7, are then placed in the troughs, as usual, and the 35 troughs filled with concrete up to the level of the upper edges of the boards, the concrete also being laid upon the top of the partitions, and joining with the concrete girders. It is to be understood that at the 40 partitions, the reinforcing rods 8, are placed in the concrete before the trough is completely filled. In case of a long span, the tiles or other members of the wall or partition, are spaced apart at the intersection 45 with the girders and that boards or planks are placed against the adjacent ends of the wall or partition to make a form or mold into which is deposited concrete to form a concrete column. When the structure is 50 complete, all of the girders are bonded together by the crosswise reinforced course of concrete 10, and the whole is a light, substantial, fire-proof and sound-proof structure. The flooring boards 19, are nailed to 55 the wooden frame work to complete the floor, and the boards or planks 20, and stag-

ing 21, are removed after the concrete girders are set.

More or less variation of the exact details of construction is possible without departing from the spirit of this invention. I desire, therefore, not to limit myself to the exact form of construction shown and described, but intend in the following claims to point out all of the invention disclosed herein. 60 65

I claim as new and desire to secure by Letters Patent:

1. A building construction comprising walls or partitions having a course of concrete formed therein at the floor, reinforced concrete girders located at said course of concrete, rows of ceiling tiles interlocked 70 with said girders and flush with the lower edges thereof, floor supporting boards which extend parallel with the girders, certain of which are contiguous therewith and primarily form the sides of the forms for the girders, the other floor supporting boards being located between said boards, cross- 75 wise extending boards at the partitions and primarily forming sides for the molds for said course of concrete, other crosswise ex- 80 tends boards between said first mentioned crosswise extending boards, all of said boards being secured together to provide a 85 frame, and flooring secured to said frame.

2. A building construction comprising walls or partitions having a course of concrete formed therein at the floor, reinforced concrete girders located at said course of concrete, rows of ceiling tiles interlocked 90 with said girders and flush with the lower edges thereof, floor supporting boards which extend parallel with the girders, certain of which are contiguous therewith and primarily form the side of the forms for the girders, the other floor supporting boards being located between said boards, crosswise ex- 95 tends boards at the partitions and primarily forming sides for the molds for said course of concrete, other crosswise ex- 100 tends boards between said first mentioned crosswise extending boards, blocks on said walls or partitions, the upper faces of which are flush with the upper faces of the tiles, and horizontal, lengthwise extending boards 105 between the intermediate lengthwise extending boards and resting on said tiles and blocks and secured to said blocks, all of said boards being secured together to form a 110 frame, and flooring secured to said frame.

ANDREW WICKEY.
